UNITED STATES PATENT OFFICE.

JOHN W. FORSYTHE, OF EDGEWOOD PARK, AND FRED N. HAYS, OF PITTSBURGH, PENNSYLVANIA.

BIN GATE.

Application filed August 8, 1921. Serial No. 490,549.

To all whom it may concern:

Be it known that we, JOHN W. FORSYTHE and FRED N. HAYS, citizens of the United States, and residents, respectively, of Edgewood Park and Pittsburgh, both in the county of Allegheny and State of Pennsylvania, have invented certain new and useful Improvements in Bin Gates, of which the following is a specification.

10 This invention relates to the outlets or discharge ports or bins or hoppers, lorry cars, and the like, and more particularly to means for forming a seal between the discharge ports or outlets of such devices and the inlets or receiving ports of a bin, hopper, or other receptacle.

One object of the invention is to provide a seal which is movable into and out of sealing position, and which is actuated by the 20 mechanism used in opening the gate or shutter controlling the outlet or discharge port of a bin or hopper, or other receptacle.

Another object of this invention is to provide a sealing mechanism which consists of 25 few parts, is readily and cheaply manufactured, and is strong and durable.

The above and other objects of our invention will be more fully explained hereinafter and illustrated in the accompanying drawings forming part of this specification, in which—

30 Figure 1 is a sectional side elevation showing one arrangement of apparatus embodying our invention.

Figure 2 is an end elevation of the apparatus of Figure 1.

Figure 3 is a side elevation, partly broken away, showing a portion of the apparatus of Figures 1 and 2, with the sealing means or 40 ring forming a novel feature of our invention in raised or inoperative position.

Figure 4 is a side elevation similar to that of Figure 3, showing the sealing means or ring in lowered or operative position.

45 Figure 5 is a side elevation similar to that of Figure 4, showing further details of the lifting mechanism by which the sealing ring is manipulated, with the sealing ring in operative position.

50 Figure 6 is a side elevation like that of Figure 5, showing the sealing ring and ring operating mechanism in lifted or inoperative position.

In the drawings in which our invention is 55 shown applied to apparatus used in handling

finely divided materials such as iron ore, flue dust, ashes, and the like, the apparatus comprises a delivery or discharge conduit A leading from an overhead bin or hopper, a lorry car B which receives the materials 60 discharged from the conduit A, and a receiving conduit C into which materials are discharged from the lorry car B. It is to be understood that the receiving conduit C is located at a distance from the conduit A, the 65 lorry car B being used to transport materials from the conduit A to the conduit C.

The lorry car B comprises a wheeled truck 2, which travels on the track formed by the rails 3, and a body portion 4. The upper 70 end or top of the body 4 is closed, with the exception of the inlet opening or port 5, this port having an annular ring or shoulder 6 projecting upwardly and terminating in an outwardly extending flange 7. The bottom 75 8 of the car body 5 is frusto-conical and has a depending straight or vertically walled outlet port 9. A second depending vertical wall, which is spaced from the wall of the outlet port 9, forms a 80 skirt for supporting the operating mechanism by which the gate or shutter 11 and the sealing ring 12 are manipulated in opening and closing the shutter 11 and ring 12.

The gate 11, which as shown, is of the 85 rocking type, is adapted to swing into and out of closing engagement with the lower edge of the wall forming the port 9. This gate has a closure portion 13, which is of considerably greater width than the port 9 90 and side members 14 and 14^a. The upper end of the side members are provided with integral stub shafts or pivot pins 15 and 15^a respectively, which extend outwardly at right angles to the side members 14, 14^a, and 95 are journaled in bearings 16 formed in the wall or skirt 10.

The sealing means or ring 12 is telescoped over the wall or skirt 10 and is free to slide or move vertically relative thereto. The 100 space between the ring 12 and wall or skirt 10 is sealed and made dustproof by means of a renewable packing 17, this packing being made of asbestos, rubber, or like material, and being removably secured to the 105 lower edge of the skirt 10 so as to bear against the inner surface of the sealing ring 12.

The stub shaft or pin 15^a, which is longer than the stub shaft 15, has a gear 18 keyed 110

thereon through which power is transmitted to the gate 11 in swinging or rocking the gate to open and close the discharge port or outlet 9. The gear 18 meshes with a spur pinion 5 19 on the shaft 20 which is journaled in a bearing 21 and in a bearing 22 on the lower end of the bracket 23 which depends from the sloping bottom of the lorry car body 4. The shaft 20 extends through the bearing 10 22 and has a sprocket wheel 24 keyed on one end thereof which is operatively connected by the sprocket chain 25 to the sprocket wheel 26 on the shaft 27. The shaft 27, which is mounted in a bearing on the body 15 4 of the car A is provided with a hand wheel 28, so that when the hand wheel is turned motion will be communicated, through the sprocket wheels 24 and 26 and chain 25, to the shaft 20 and, through the shaft 20, to the gears 19 and 18 and rock shaft 15^a, so 20 as to swing or rock the gate or shutter 11.

The stub shafts 15 and 15^a have levers 30 and 30^a keyed thereon to turn with the shafts, and the ends of these levers which 25 are fixed to the shafts, are provided with spur gear teeth 31 so as to form a segmental and mutilated gear. Another pair of levers 32 and 32^a, which are mounted to turn on stub shafts 33 and 33^a fixed to the wall 10, 30 have similarly arranged spur gear teeth 34 which mesh with the teeth 31 on the levers 30 and 30^a, so that when the hand wheel 28 is turned the levers 30 and 30^a, 32 and 32^a, are caused to swing in unison.

35 Each of the levers 30, 30^a and 32, 32^a is pivotally connected at its swinging end to one end of a link 35, and the lower depending end of the links 35 are bent to form hooks 36 which engage with anti-friction 40 rollers 37 secured by pins to the lifting ears or lugs 38 on the sealing ring 12, in raising and lowering this sealing ring into and out of operative position.

The delivery or discharge conduit A of 45 Figures 1 and 2 is shown provided with the same sealing mechanism and gate or shutter mechanism as that on the discharge port or outlet 9 of the lorry car B, and in referring to this mechanism the same reference numerals are used to designate like parts. However instead of employing the hand wheel 28 in the manner which has been described, the sprocket wheel 28^a, is mounted on the shaft 27^a which carries a pinion gear 26^a, 50 and this gear 26^a meshes directly with a gear 24^a on the end of the shaft 20. A sprocket chain 40, which is trained over the sprocket wheel 28^a and over a pair of idler sprocket wheels 41 and 42 which are 55 60 rotatably mounted on a support 43, is employed to operate the lifting mechanism in moving the sealing ring 12 into and out of operative position on the delivery conduit A.

It will be noted that the travel of the 65 gate or shutter 11 that is necessary in or-

der to open and close the conduit 9 is considerably greater than the travel of the sealing ring 12 that is required to move the ring into and out of its operative position and, therefore, in order to move the sealing ring into operative position before the outlet port 9 begins to open and to entirely close the outlet port 9 before the sealing ring commences to move from its operative position with a single operating mechanism, it is necessary to provide for considerable lost motion in the operating mechanism.

In the operation of our improved apparatus in connection with the lorry car B, the car will be moved on the track rails 3 until the outlet port 9 is directly above the receiving conduit C.

The hand wheel 28 will then be moved so as to turn the shaft 20. At the commencement of the turning movement of the shaft 20, the links 35 will start to move downwardly, and at the same time the shutter or gate 13 will start to swing. Turning movement of the shaft 20 is continued, and when the sealing ring 12, which moves downwardly by gravity rests upon the flange 7^a of the receiving conduit C, the gate 13 will still be in port closing position, this gate being made long enough to make this possible. 90 Further turning movement of the shaft 20 continues the swinging movement of the shutter or gate 13 and gradually uncovers or opens the port 9 so as to permit materials within the body portion 4 of the lorry car 100 to flow by gravity into the receiving conduit C. It will be noted that as the sealing ring had moved downwardly into sealing position before the gate 11 commenced to open, that the escape of dust or finely divided solids from between the lower end of the port 9 and upper end of the receiving conduit C is prevented and overcome. After the sealing ring 12 becomes seated upon the flange 7^a of the conduit C, the hooks on the 110 ends of the links 35 move downwardly out of engagement with the anti-friction rollers 37 on the pins secured to the lugs or ears 38 on the sealing ring 12, this downward movement of the links 35 being continued 115 until the gate or shutter 11 is in port opening position.

After the body 4 of the lorry car is emptied of its contents, the hand wheel 28 is moved in the opposite direction. At the 120 commencement of this reverse movement the gate or shutter 11 is moved into port closing position and the port is entirely closed before the hooks 36 on the ends of the links 35 engage with 125 the anti-friction rollers 37. As soon as the conduit 9 is entirely closed the hooks 36 engage the anti-friction rollers 37 and start to lift the sealing ring into 130 inoperative position, or from the position

shown in Figure 4 into that shown in Figure 3. During the time the ring 12 is being lifted, the gate 11 continues to move but without uncovering the port 9. It also will be noted that the sealing ring remains in sealing position until the gate 11 is returned to its closing position below the port 9.

The lorry car will then be transferred into position to receive another load of the materials being handled by moving it into position immediately beneath the discharge or outlet conduit A.

The operation of the sealing ring on the outlet A is substantially the same as that of the ring on the bottom of the lorry car, one exception being that the sprocket chain 40 is employed to actuate the operating mechanism instead of the hand wheel 28.

The many advantages of our invention, which will be appreciated by those skilled in the art, arise from the use of the sealing ring by which a discharge port is connected to a receiving conduit so as to prevent the escape of dust into the surrounding atmosphere.

While one specific embodiment of our invention is shown and described herein, it is to be expressly understood that the invention is not limited thereto, since various modifications in the construction and application of apparatus embodying our invention may be made without departing from the invention as defined in the appended claims.

35 We claim—

1. The combination with a receptacle having a discharge port, of a gate for controlling said port, a reciprocable sealing ring mounted around said port adapted to seal said port with the inlet port of a receiving bin, means for operating said gate, and means connecting said gate and said sealing ring, said last named means being adapted to automatically move said sealing ring into sealing engagement with said inlet port upon the operation of said gate operating means prior to the opening of said gate.

2. The combination with a receptacle having a discharge port, of a rocking gate for controlling said port, a vertically reciprocable sealing ring mounted around said port adapted to seal said port with the inlet port of a receiving bin, means for rocking said gate to open and closed position, and means connecting said gate and said sealing ring, said last named means being adapted to automatically lower said sealing ring

when said gate is rocked to open position and to raise said sealing ring when said gate is rocked to closed position.

3. The combination with a receptacle having a discharge port, of a rocking gate for controlling said port, a vertically reciprocable sealing ring mounted around said port adapted to seal said port with the inlet port of a receiving bin, means for rocking said gate to open and closed position, and means operated by said gate for lowering said sealing ring into sealing position and raising said gate out of sealing position, said means being adapted to lower said sealing ring into sealing position prior to the opening of said gate and to raise said sealing ring out of sealing position only after said gate is in closed position.

4. The combination with a receptacle having a discharge port, and a receiving bin having an inlet port, of a gate for controlling said discharge port, a reciprocable sealing ring around said discharge port adapted to seal said discharge port with said inlet port of the receiving bin, means for operating said gate, and means operable by the gate for moving said sealing ring into sealing position prior to the opening of said gate.

5. The combination with a receptacle having a discharge port, of a gate for controlling said port, a reciprocable sealing ring mounted around said port adapted to seal said port with the inlet port of a receiving bin, means for operating said sealing ring and said gate, said means being adapted to move said sealing ring into operative position prior to the opening of said gate, and comprising rocking shafts on said gate, means for rotating said shafts and said gate, a lever secured to each of said shafts, gear teeth formed on the end of said levers adjacent said shaft, other levers mounted on stub shafts to the one side of said rocking shafts, gear teeth formed on the end of said last named levers nearest said stub shaft, said teeth on said last named levers being in mesh with the teeth on said first named levers, links pivotally secured to the free ends of said levers and having their other ends removably secured to suitable lugs formed on said ring.

In testimony whereof, we have hereunto set our hands.

JOHN W. FORSYTHE.
FRED N. HAYS.
